WATERPROOF FLASHLIGHT SWITCH

Joseph A. Gits and Jules P. Gits, Chicago, Ill.

Application April 19, 1946, Serial No. 663,521

14 Claims. (Cl. 200—60)

1

This application relates to flashlights and more particularly to watertight flashlights.

The invention is directed particularly to an improved watertight connection between the casing of the flashlight and the external switch mechanism for opening and closing the electrical circuit.

Flashlights are portable lights including a casing adapted to hold one or more electric cells within it. At one end thereof there is a bulb and reflector combination along with a ring for holding the bulb and reflector within the casing, and at the other end there is a cap for closing the casing and holding the cells therein. Electric conductors are arranged within the casing so as to contact the cells at one end and to contact some other part of the flashlight mechanism to complete an electric circuit, usually the reflector. To operate the flashlight, contacts are electrically associated with the conductors inside of the casing, the contacts being brought out through the casing whereby the circuit may be completed externally. Since the contacts pass through the casing, it is desirable that they be sealed in some manner so that water, for example, will not penetrate the casing at the contacts, and furthermore, in order to prevent short circuiting thereof, it is desirable that water be kept away from the contacts where they are external of the casing.

Accordingly, it is an object of the invention to provide an improved watertight flashlight in which contacts are brought through the flashlight casing and are sealed to the outside so that any external substance is prevented from entering the flashlight casing where the contacts penetrate it, and is prevented from coming into contact with the contacts while still permitting the contacts to be operated externally of the flashlight casing.

It is also an object of the invention to provide an improved external contact operating mechanism.

In carrying out the invention in one form, a casing and conductors inside thereof for connection to a source of current are provided. A continuous ridge extends outwardly from the exterior of the casing to define a well, and contacts are arranged to project into the well from the inside of the casing for completing a circuit exteriorly thereof between electric conductors interiorly thereof. A water impermeable membrane overlies the top of the ridge and extends along its exterior sides, and a rigid cap having sides de-

2

pending therefrom overlies the membrane and tightly holds it against the top and exterior sides of the ridge in a watertight relation. Means are associated with the cap for operating the contacts through the membrane. More particularly, a switch mechanism for a flashlight is provided which comprises in combination a pair of contacts, a resilient member in fixed electrical contact with one of the contacts and overlying the other of the contacts in a non-electrical contact position, a depressible member, and a slide member having an inoperative position and a pair of operative positions. A pair of means on the slide for engaging the depressible member are provided along with a push button member overlying one of the pair of means. Barrier means are arranged between the slide and the depressible member so that in the inoperative position of the slide, both of the pair of means are blocked from contacting the depressible member, the push button member in the first of the operative positions of the slide member being effective to intermittently move one of the pair of means into contact with the depressible member, and in the second of the operative positions of the slide member the other of the pair of means is in continuous contact with the depressible member.

For a more complete understanding of the invention, reference should now be had to the accompanying drawings in which:

Figure 1 is a side view of the flashlight embodying the invention;

Fig. 2 is an enlarged sectional view taken substantially along the lines 2—2 of Fig. 1;

Fig. 3 is a sectional view taken substantially along lines 3—3 of Fig. 2;

Fig. 4 is an enlarged fragmentary view of Fig. 2 illustrating the position of the parts when the switch is in off-position;

Fig. 5 is a view similar to Fig. 4 illustrating the parts when the switch is in signaling position;

Fig. 6 is a view similar to Fig. 4 illustrating the parts when the switch is in on-position;

Fig. 7 is a sectional view taken substantially along lines 7—7 of Fig. 4;

Fig. 8 is a sectional view taken substantially along lines 8—8 of Fig. 4;

Fig. 9 is a sectional view taken substantially along lines 9—9 of Fig. 4; and

Fig. 10 is an exploded perspective view of the parts comprising the flashlight switch.

Referring more particularly to the drawings,

the invention is shown embodied in a flashlight comprising a casing 9 including a barrel portion 10 and a head 11 extending at right angles thereto, the barrel being of generally cylindrical shape having a diameter and a length to accommodate the desired number of electrical cells 12, of which two are shown (Fig. 2 only) for purposes of illustration. The casing 9 is made of water impermeable material, such for example as any plastic product suitable for the purpose such as ethyl or acetate cellulose, and may be formed by injection molding, for example, to include corrugations 13 on the exterior of the casing providing a firm gripping surface. At the end of the casing, opposite to the head 11, there is a circumferential flange 14 to the right of which the casing is provided with a plurality of external threads 15. A hollow cap 16, which may also be made by injection molding of a material similar to that of casing 9, is provided with interior threads 15a for cooperation with exterior threads 15 to screw the cap 16 on the casing. To assure that the connection between casing 9 and cap 16 is watertight, a gasket 17 is arranged to lie against one side of flange 14, the edge of cap 16 having a pointed circular ridge 18 which bites into gasket 17 when cap 16 is tightly screwed on. Furthermore, the surfaces of the threads 15 on the casing bear against corresponding surfaces of threads 15a in cap 16 so that by tightly screwing the cap 16 on the casing, a further watertight connection is provided.

The cap 16, being hollow, may conveniently receive a U-shaped member 19 which slips inside thereof and has a spring bracket 21 attached for holding a spare bulb 22. The U-shaped member 19 is held within cap 16 by means of a conical spring 23, the lower coil of which bears relatively tightly against the inside of the cap 16 at the end of the threads 15a, the spring 23 also being used to complete the electrical circuit with one end of one of the cells 12 as is well understood.

The angular head 11 of the flashlight has a series of external threads 24, and to cooperate with these threads to hold the ring 25 to the casing, the ring has internal threads 24a. An inwardly projecting ledge 26 extends around ring 25 and holds a crystal or face 27 to the casing. The ring 25 may be made of plastic material by injection molding and the crystal 27 may be made of any suitable clear material which is unbreakable in character. Thus the flashlight casing including the crystal 27 is of a durable character and may be dropped on hard surfaces without chipping or cracking.

A reflector 28, of any desired shape, is adapted to be held in the angular portion 11 and has a series of threads 29 at one end, into which a sleeve or bushing 31 is threaded for holding a bulb 32 attached to the reflector. Thus the reflector and bulb comprise a single assembly. The reflector includes a rim 33 which in the assembled form of the flashlight lies against a washer 34, the washer in turn bearing against one edge of head 11. A washer 35 lies against the outer side of rim 33 and is in turn contacted by the crystal 27 so that when ring 25 is screwed onto head 11, a watertight connection is formed by the washers, the threads 24 and 24a binding against each other to increase the effectiveness of the watertight connection.

At the junction of angular head 11 and the casing proper inside thereof, there is an integrally formed bridging member 36 to which a resilient contact member 37 is attached at its center at

one end by means of a rivet or similar element 38, the rivet forming a contact for one of the cells 12 as shown best in Fig. 2. The other end of resilient member 37 contacts the exposed end of bulb 32, forming part of the electrical circuit within the flashlight. Conductors 39 and 41, made of flat conducting strips, for example, are attached to the inside of the casing and lie within a channel formed by two integrally molded ridges 42 and 43 extending inwardly from the inside of the casing, the conductor 41 being attached at one end to the casing by means of a rivet 44. The rivet 44 also connects this conductor to an annular shell 45 fitting within the end of the flashlight casing, the shell 45 having a rim as shown which contacts the largest convolution of spring 23 thereby to contact one end of one of the cells 12. The conductor 39 extends in the opposite direction to that of conductor 41 and is attached to the casing by means of rivets 46 and 47. At the forward end of conductor 39 there is a ledge or shelf 48 provided on the casing for supporting the conductor, and the conductor is provided with a resilient right angularly extending portion 49 for engaging the reflector 28. At the rear of the head 11 a bracket or clip 51 is attached such as by riveting, for example, so that the flashlight may be clipped to a carrying belt.

As thus far described, the flashlight casing is one which is of a watertight character and may therefore be immersed in water for long periods of time without effecting the operation thereof.

The conductors 39 and 41 have their inner ends arranged adjacent each other, the conductor 41 being further attached to the casing by means of a rivet 52. The rivets 46 and 52 extend completely through the casing wall, and in order that the heads of these rivets may not bite into the casing wall and injure it, these rivets also extend through a reinforcing strip 53 which serves as a surface over which the heads of the rivets are formed.

Surrounding rivets 46 and 52 and the reinforcing strip 53, there is a continuous ridge 54 of generally rectangular shape which is integrally formed with the outer wall of the flashlight casing and extends outwardly therefrom as shown. The inner surface of continuous ridge 54 defines a well or depression 55 in which the external contacts of the flashlight electrical circuit are maintained. The top surface 55 of the continuous ridge 54 is flat and the outer side walls 56 are curved outwardly as shown for a purpose to be described. In order to seal the well 55 in a watertight manner, a water impermeable membrane 57 is arranged to overlie ridge 54 along the top surface 55 as well as along the side surfaces 56, the membrane 57 covering the space inside of ridge 54. The membrane may be made of any water impermeable substance such as rubber or rubber substitutes, for example.

Inside of well 55 and attached to the casing at one end by means of rivet 52 is a resilient or spring member 64 biased outwardly from insulating strip 53. At the other end of resilient member 64 there is a contact 65 for cooperation with one end of rivet 46 to close the electrical circuit between conductors 39 and 41 when resilient member 64 is depressed. Normally contact 65 is not in engagement with the head of rivet 46 by virtue of the fact that the resilient member 64 is biased outwardly. The member 64 together with the outer end of rivet 46 lying inside of membrane 57 are completely sealed from the outside as will become clear.

A metallic cap 58 of generally rectangular shape similar to that of ridge 54 has a top surface 59 and depending side walls forming a skirt 61 extending below top surface 59, the skirt 61 curving outwardly with a curvature similar to that of outer side walls 56 and forming a substantially rigid structure. The skirt 61 is slightly larger than the outer periphery of ridge 54, so that in the assembled condition of the flashlight when membrane 57 is placed so as to overlie ridge 54 with portions thereof extending downwardly along outer side walls 56 and cap 58 is placed so as to overlie membrane 57, and is tightly held to the casing by means of rivets 62 and 63, for example, the skirt 61 forces membrane 57 tightly against outer curved walls 56 of the ridge 54. The curved surfaces of skirt 61, as cap 58 is forced downwardly, bind the water impermeable membrane tightly against ridge surfaces 56 to form a watertight connection. In addition, the top surface 59 forces membrane 57 against top surface 55 of the ridge also to form a tight seal. Referring to Figs. 4, 5, and 6, and to Fig. 9, it will be seen that skirt 61 cooperates with the surfaces 56 to form the watertight connection at all points around ridge 54. In the foregoing manner, water or any other substance is prevented from passing into well 50.

The top surface 59 of cap 58 is provided with an opening 66 through which one end 67 of a resilient member 68 projects, as shown best in Figs. 4, 5, and 6, the other end of member 68 being attached to top surface 59 by means of a rivet 69. The resilient member 68 extends along the underside of surface 59, the end 67 projecting up through opening 66 and being bent angularly upwardly as shown.

Adapted to lie on top of cap 58 is the external operating mechanism for the flashlight contacts and includes a shell 71, a slide 72, a push button 73, and a thumbpiece 74. The shell 71 is generally rectangular in shape having downwardly depending side walls 75, and a top 76 which cooperates with top surface 59 to form a space within which the slide 72 is adapted to move. Extending at right angles and outwardly from the end portions of side walls 75 are the tongues 76 and 77 which are provided with holes to receive respectively the rivets 62 and 63 for attaching shell 71 as well as metallic cap 58 to the flashlight housing. As shown best in Fig. 9, side walls 75 of shell 71 bear directly on top of cap 58 so that there is a continuous pressure exerted downwardly on cap 58 at every point around the periphery, even though only two rivets are used, one at each end and since cap 58 is substantially rigid in form there is uniform contact of the skirt 61 against membrane 57 and hence of the membrane against side walls 56. Thus the seal of well 56 from the outside is made more effective.

Referring to Fig. 10, the top 76 of shell 71 is provided with three corrugations 78 between two lengthwise extending slots 79 adjacent the rear portion of shell 71. Adjacent the forward portion of the shell there is a circular opening 81. The corrugations 78 and the slots 79, as well as the opening 81, may be formed in any well known manner such as by a stamping operation, for example.

The slide 72 is a generally rectangular member somewhat narrower in width and shorter in length than the inside of shell 71, so as to be easily movable back and forth, an upwardly extending resilient tongue 82 being formed adjacent the rear portion thereof to engage with any one of

corrugations 78 for holding the slide in one of its three positions. Depending downwardly from the front end of slide 72 is a ledge 83 for cooperation with angular portion 67 of resilient member 68 to actuate the flashlight contacts in one position of slide 72. Also projecting downwardly adjacent the forward end of slide 72 is a resilient tongue 84 which may be formed by stamping a suitable portion out of slide 72 followed by a proper bending operation. The tongue 84 resiliently biases the ledge 83 out of contact closed position in the signaling position of slide 72, and it acts to hold angularly extending portion 67 in constantly closed contact operating position in on-position of the slide. In order to depress ledge 83 during signaling operation of the flashlight, the push button 73 is arranged to move in the opening 81, the push button 73 being a cylindrical cup shaped member having a flange 85 somewhat larger in diameter than the opening 81, whereby the cup member is maintained in this opening.

The slide 72 is moved back and forth by thumbpiece 74. The thumbpiece 74 is a cup shaped member having corrugations 86 along its top surface for giving a good grip thereto, is provided with horizontal flanges 86 extending around the major portion thereof to form a good sliding surface with the top 76 of shell 71. The thumbpiece 74 is further provided with downwardly extending fingers 87 which project through slots 79 and are bent around the slide 72, cut-out portions 88 being provided in the slide to receive tongues 87. The tongues 87 bent around slide 72 hold the upwardly extending tongue 82 in one of corrugations 78. Thus when the thumbpiece 74 is moved back and forth, the slide 72 is also moved back and forth.

The assembly of the contact operating mechanism will be clear by considering Fig. 4 and Fig. 10, for example. The push button 73 is inserted into opening 81 followed by placing in position of slide 72 with the tongue 82 projecting into one of the corrugations 78 and the tongue 84 extending downwardly. The thumbpiece 74 is placed in a position overlying cap 71 with the tongues 87 projecting through slots 79, after which the tongues are bent around the slide 72 within cut-out portions 88. Following these steps of assembling, the shell 71 is placed in position overlying cap 58 and the rivets 62 and 63 are placed through the registering openings in the various members and are riveted over. The portion of rivet 63 inside of casing 10 passes through an opening in conductor 41, is insulated therefrom by means of gasket 60 so that the metallic portions of cap 58 and shell 71 do not complete the electrical circuit of conductors 39 and 41, the washer 70 being provided to prevent the head of rivet 63 from slipping through gasket 60.

The operation of the mechanism may best be understood by referring to Figs. 4, 5, and 6. In Fig. 4, the mechanism is in the position where the flashlight may not be turned on. That is, no amount of depressing of push button 73 will result in lighting of the light. In this position tongue 82 is in the first of corrugations 78, tongue 84 is in contact with the top surface 59 of cap 58, and ledge 83 is in a position so that when push button 73 is depressed ledge 83 also comes into contact with the top surface 59. Accordingly, the top surface 59 may be termed a barrier to prevent operation of the flashlight. In the second or signaling position of the operating mechanism, shown in Fig. 5, the thumbpiece 74 has been pushed forwardly so that tongue

82 is in the second or middle one of corrugations 78. Then ledge 83 overlies angularly extending portion 67 while the tongue 84 is still in contact with top surface 59. In this position when push button 73 is depressed, ledge 83 comes into contact with angularly extending portion 67 thereby depressing this member, causing the resilient member 68 to move away from top surface 59 and exert a closing force on resilient member 64 through the membrane 57, thereby effecting engagement of the contact 65 and the rivet 46 to close the circuit between conductors 39 and 41. The force exerted by member 68, through membrane 57, is at right angles to the membrane and hence there is no sliding wear thereof. When the push button 73 is released, resilient tongue 84 causes ledge 83 to move upwardly, and the push button 73 to move outwardly. At the same time, the resilience of member 68 causes this member to assume its original position, whereupon resilient member 64 biases the contact 65 out of engagement with rivet 46. Accordingly, an intermittent operation of the flashlight is obtained by depressing and releasing the push button 73.

In the third position of the contact operating mechanism, shown in Fig. 6, the thumbpiece 74 has been moved forwardly so that the tongue 82 is in the third one of corrugations 78. In this position of slide 72, the tongue 84 has moved forwardly and has moved up onto angular portion 67 of member 68. The resilience of tongue 84 combined with the angularly extending portion 67 creates a downward force on resilient member 68, causing this member to close contact 65 and rivet 46 into a constantly closed condition. Depressing push button 73 will cause ledge 83 to move into contact with angular portion 67, but this produces no additional operative effect. The thumbpiece 74 is slideable in either direction and to move slide 72 to either the first or second positions, it is only necessary to move thumbpiece 74 rearwardly.

Without further elaboration, the foregoing will so fully explain the gist of our invention that others may, by applying current knowledge, readily adapt the same for use under varying conditions of service, without eliminating certain features, which may properly be said to constitute the essential items of novelty involved, which items are intended to be defined and secured to us by the following claims.

We claim:

1. In an article of the class described, a casing, conductors inside of said casing for connection to a source of current adapted to be disposed inside of said casing, a continuous ridge extending outwardly from the exterior of said casing and defining a well, contacts in said well for completing a circuit exteriorly of said casing between said conductors interior of said casing, a water impermeable membrane overlying the top of said ridge and extending along the exterior sides thereof, a rigid cap having a top and sides depending therefrom overlying said membrane and tightly holding said membrane against the top and exterior sides of said ridge in a waterproof relation, and means extending through the top of said cap for operating said contacts through said membrane.

2. In an article of the class described, a casing, conductors inside of said casing for connection to a source of current adapted to be disposed inside of said casing, a continuous ridge extending outwardly from the exterior of said casing and

defining a well, contacts in said well for completing a circuit exteriorly of said casing between said conductors interior of said casing, a water impermeable membrane overlying said ridge, a rigid cap having a top and depending flanges for tightly holding said membrane against the top and sides of said ridge in a waterproof relation, and means extending through the top of said cap for operating said contacts through said membrane.

3. In an article of the class described, a casing, conductors inside of said casing for connection to a source of current adapted to be disposed inside of said casing, a continuous ridge having angularly depending sides extending outwardly from the exterior of said casing and defining a well, contacts in said well for completing a circuit exteriorly of said casing between said conductors interior of said casing, a water impermeable membrane overlying the top of said ridge and extending along said angularly depending sides, a rigid cap having a top and angularly depending flanges overlying said membrane, said top tightly holding said membrane against the top of said ridge, said angularly depending flanges forcing said membrane against the angularly depending sides of said ridge, thereby to form a watertight seal over said well, and means extending through the top of said cap for operating said contacts through said membrane.

4. In an article of the class described, a casing, conductors inside of said casing for connection to a source of current adapted to be disposed inside of said casing, a continuous ridge having exterior angularly depending sides integrally formed with and extending outwardly from the exterior of said casing, said ridge defining a well, contacts in said well for completing a circuit exteriorly of said casing between said conductors interior of said casing, a water impermeable membrane overlying the top of said ridge and lying along said exterior angularly depending sides, a rigid cap having a top and angularly depending sides overlying said membrane, said top tightly holding said membrane against the top of said ridge, said angularly depending sides forcing said membrane against the depending sides of said ridge, thereby to form a water-tight seal over said well, and means extending through the top of said cap for operating said contacts through said membrane.

5. In an article of the class described, a casing, conductors inside of said casing for connection to a source of current adapted to be disposed inside of said casing, a continuous ridge having exterior angularly depending sides integrally formed with and extending outwardly from the exterior of said casing, said ridge defining a well, contacts in said well for completing a circuit exteriorly of said casing between said conductors interior of said casing, a water impermeable membrane overlying the top of said ridge and lying along said exterior angularly depending sides, a housing having a downwardly angularly depending flange overlying said membrane, said angularly depending flange forcing said membrane against the depending sides of said ridge, thereby to form a watertight seal over said well, and pressure exerting means in said housing for operating said contacts through said membrane.

6. In an article of the class described, a waterproof casing, conductors inside of said casing connected to a source of current adapted to be disposed inside of said casing, said conductors

having ends thereof adjacent each other, terminals in electrical association with said adjacent ends and extending through said casing, a normally open spring contact on the outside of said casing attached to one of said conductors by one of said terminals and adapted when closed to contact the other of said terminals, a switch housing arranged over said contacts, a three position slide having two contact actuating means in said housing, a barrier between said two contact actuating means and said contacts, and a push button overlying said slide, in one position of said slide both of said contact actuating means being blocked by said barrier, in a second position of said slide one of said contact actuating means being in a position to actuate said spring contact only when the push button is depressed and in a third position the second of said contact actuating means maintains said spring contact permanently closed.

7. In an article of the class described, a waterproof casing, conductors inside thereof for connection to a source of current adapted to be disposed inside of said casing, said conductors having ends thereof adjacent each other, terminals in electrical association with said adjacent ends and extending through said casing, a normally open spring contact on the outside of said casing attached to one of said conductors by one of said terminals and adapted when closed to contact the other of said terminals, a switch housing arranged over said contacts one wall of which forms a barrier, a spring contact actuating member attached to the underside of said barrier, a three position slide inside of said housing, said slide including two actuating means, and a push button extending through said housing and overlying said slide, in one position of said slide both of said actuating means being blocked by said barrier, in a second position of said slide one of said actuating means being in a position to effect actuation of said contact actuating means only when the push button is depressed and in a third position the second of said actuating means maintains said contact actuating means in permanently closed contact position.

8. In an article of the class described, a waterproof casing, conductors inside thereof for connection to a source of current adapted to be disposed inside of said casing, said conductors having ends thereof adjacent each other, terminals in electrical association with said adjacent ends and extending through said casing, a normally open spring contact on the outside of said casing attached to one of said conductors by one of said terminals and adapted when closed to contact the other of said terminals, a switch housing arranged over said contacts, one wall of said housing forming a barrier, another wall of said housing having three stops arranged thereon, a three position slide having two contact actuating means and a stop engaging member in said housing, and a push button overlying said slide, in one position of said slide the stop engaging member engages one of said stops and both of said contact actuating means are blocked by said barrier, in a second position of said slide the stop engaging member engages a second one of said stops and one of said contact actuating means is in a position to actuate said spring contact only when the push button is depressed, and in a third position of said slide said stop engaging member engages the third of said stops and the second of said contact actuating means maintains said spring contact constantly closed.

9. In an article of the class described, a waterproof casing, conductors inside thereof for connection to a source of current adapted to be disposed inside of said casing, said conductors having ends thereof adjacent each other, terminals in electrical association with said adjacent ends and extending through said casing, a normally open spring contact on the outside of said casing attached to one of said conductors by one of said terminals and adapted when closed to contact the other of said terminals, a switch housing arranged over said spring contact, one wall of said housing forming a barrier, a spring contact actuating member attached to the underside of said barrier, another wall of said housing having three stops arranged thereon, a three position slide having two contact actuating means and a stop engaging member in said housing, and a push button overlying said slide, in one position of said slide the stop engaging member engages one of said stops and both of said contact actuating means are blocked by said barrier, in a second position of said slide the stop engaging member engages a second of said stops and one of said contact actuating means is in a position to actuate said spring contact only when the push button is depressed, and in a third position of said slide said stop engaging member engages a third of said stops and the second of said contact actuating means maintains said spring contact constantly closed.

10. In an article of the class described, a waterproof casing, conductors inside thereof for connection to a source of current adapted to be disposed inside of said casing, said conductors having ends thereof adjacent each other, terminals in electrical association with said adjacent ends and extending through said casing, a normally open spring contact on the outside of said casing attached to one of said conductors by one of said terminals and adapted when closed to contact the other of said terminals, a switch housing arranged over said contacts, one wall of said housing forming a barrier, another wall of said housing having three stops arranged thereon, a three position slide having a stop engaging member, actuating means and a resilient member urging said contact actuating means to an inactive position, a spring contact actuating member attached to the underside of said barrier, a push button overlying said slide, in one position of said slide the stop engaging member engages one of said stops and said actuating means is blocked by said barrier, in a second position of said slide said stop engaging member engages another of said stops and said actuating means is in a position to cause said spring contact actuating member to close said normally open spring contact against the biasing force of said resilient member only when said push button is depressed, and in a third position of said slide the stop engaging means engages a third of said stops and said resilient member holds said spring contact actuation member to effect constant closure of said normally open spring contact.

11. In an article of the class described, a waterproof casing, conductors inside thereof for connection to a source of current adapted to be disposed inside of said casing, said conductors having ends thereof adjacent each other, terminals in electrical association with said adjacent ends and extending through said casing, a reinforcing strip externally of said casing for holding one of the ends of each of said terminals spaced from said casing, a normally open spring contact on

the outside of said casing attached to one of said conductors by one of said terminals and adapted when closed to contact the other of said terminals, a switch housing arranged over said contacts, one wall of said housing forming a barrier, another wall of said housing having three stops arranged thereon, a three position slide having a stop engaging member, a contact actuating means and a resilient member urging said contact actuating means to an inactive position, and a push button overlying said slide, in one position of said slide the stop engaging member engages one of said stops and said contact actuating means is blocked by said barrier, in a second position of said slide said stop engaging member engages another of said stops and said contact actuating means is in a position to actuate said spring contact against the biasing force of said resilient member only when said push button is depressed, and in a third position of said slide the stop engaging means engages a third of said stops and said resilient member holds said spring contact constantly closed.

12. Switch mechanism for a flashlight comprising in combination, a pair of contacts, a resilient member in fixed electrical relation with one of said contacts and overlying the other contact in non-contact relation, a depressible member, a slideable member disposed over said depressible member, said slideable member having a plurality of positions and being movable to effect actuation of said depressible member whereby to move said resilient member into contact with said other contact, a pair of means on said slide for engaging said depressible member, and means to effect depression also of said slideable member when in a position where one of said pair of means is engageable with said depressible member, the other of said pair of means when in a position to engage said depressible member being effective to actuate said depressible member to effect a constant contact of said resilient member and said other contact.

13. Switch mechanism for a flashlight comprising in combination, a pair of contacts, a resilient member in fixed electrical relation with one of said contacts and overlying the other of said contacts in non-contact relation, a depressible member, a slideable member having a plurality of positions and being movable to effect actuation of said resilient member whereby to move said resilient member into contact with said other contact, said slide having a pair of means thereon for engaging said depressible member, a manually depressible member overlying one of

said pair of means, means in one position of said slide for preventing movement of both of said pair of means into contact with said depressible member when said manually depressible member is depressed, said manually depressible member in another position of said slide being operative to move one of said pair of means into contact with said depressible member whereby to effect intermittent engagement of said resilient member and said other contact, in the third position of said slide member the other of said pair of means effecting constant engagement of said resilient member and said contact.

14. Switch mechanism for a flashlight comprising in combination, a pair of contacts, a resilient member in fixed electrical relation with one of said contacts, and overlying the other of said contacts in non-electrical contact relation, a depressible member, a slideable member having an inoperative position and a pair of operative positions, a pair of means on said slide for engaging said depressible member, a manually depressible member overlying one of said pair of means, and barrier means in said inoperative position of said slide blocking movement of both said pair of means into contact with said depressible member, said manually depressible member in the first of the operative positions of said slide member being effective to move one of said pair of means into contact with said depressible member whereby to effect intermittent engagement of said resilient member and said contact, and in the third position of said slide member the other of said pair of means effecting constant engagement of said resilient member and said contact.
